O. E. Duff Attorney

UNITED STATES PATENT OFFICE.

JOSEPH W. ROSS, OF ALMA, ILLINOIS.

PLANT-PROTECTOR.

SPECIFICATION forming part of Letters Patent No. 704,116, dated July 8, 1902.

Application filed February 13, 1902. Serial No. 93,956. (No model.)

To all whom it may concern:

Be it known that I, JOSEPH W. ROSS, a citizen of the United States, residing at Alma, in the county of Marion and State of Illinois, 5 have invented certain new and useful Improvements in Plant-Protectors; and I do hereby declare the following to be a full, clear, and exact description of the invention, such as will enable others skilled in the art to which

it appertains to make and use the same.

My invention relates to plant-protectors, and has for its object to provide a device of this class which is simple in construction, easy of operation, and composed of a minimum number of parts.

A further object of my invention is to provide a device of this class which may be easily raised, lowered, or tilted after the same has been securely anchored to the ground in order to shade or protect one side of the plant or, as may be frequently desired, to allow the sun to hit the plant, while the same is protected from the wind.

With these objects in view my invention 25 consists in the construction of the hood and in the manner of holding the same at the desired position on the anchor.

My invention further consists in certain other novel features of construction and in 30 combination of parts, which will be first fully described and afterward specifically pointed out in the appended claims.

Referring to the accompanying drawings, Figure 1 is a perspective view of my protector 35 in an operative position and tilted. Fig. 2 is a perspective of the same in the position of entirely covering the plant. Fig. 3 is a plan view of hood-blank, the dotted lines showing manner of folding. Fig. 4 is a perspective 40 view of my combined hood-securing piece and anchor-support.

Like numerals of reference indicate the same parts throughout the several figures, in which—

45 1 is my plant-protector, composed of the hood 2 and anchor 3.

4 indicates my combined hood-securing piece and anchor-support, through which the anchor 3 passes.

50 5 indicates a notched flap secured to the top

of the hood in any convenient manner, as by small rivets or by any means which would not be affected by dampness, the notched edge 6 being adapted to be folded down when the protector is not in use or when packing the 55 same, which packing is done by inserting one hood into the other, whereby a large number of the protectors occupy but a very small space.

In Fig. 2 I show somewhat of a modification. The flap 5 is placed nearer to edge of the top of the hood, the notched edge 6 extending over the same. I, however, prefer the former construction, as shown in Fig. 1, for the reason that they may be packed much 60 more compactly, which of course is an important feature of an article of manufacture. The said flap is made of any suitable waterproof material, but preferably of heavy oiled paper, which while combining strength and 65 durability will at the same time be pliable, so that it may be readily bent or turned up to engage the anchor.

Having thus described the several parts of my invention, its operation is as follows: The 70 anchor is planted in the ground, straddling the plant. If it is desired to entirely cover the plant, the hood is slid down the anchor, as shown in Fig. 2. When in this position, the notched edge of the top flap is raised, so 75 as to engage the anchor and hold the hood in the desired position. If, however, it is desired to protect one side only of the plant, the hood is raised on the anchor to the desired height and tilted to the desired angle. The 80 notched edge of the top flap is then turned up and engages with the anchor, which securely holds the hood in the tilted position.

The construction shown in Fig. 1 will not 85 permit angularly tilting of the hood unless 90 the top of the anchor is close enough to the hood so as to be engaged by the notched flap; but in Fig. 2 the hood may be tilted and engaged by the flap at any point along the anchor.

Having thus described my invention, I do not wish to be understood as limiting myself to the exact construction as herein set forth, as various slight changes may be made there-in which would fall within the limit and scope 95 100

of my invention, and I consider myself clearly entitled to all such changes and modifications.

What I claim as new, and desire to secure 5 by Letters Patent of the United States, is—

1. In a plant-protector the combination with a hood and an inverted-U-shaped anchor, of means carried on said hood for engaging said anchor at any point along the side 10 of said anchor, whereby the entire protector may be raised and tilted at any point, substantially as described.

2. In a plant-protector the combination of a hood, an anchor secured thereto, and a notched flap on the top of said hood adapted 15 to engage said anchor, substantially as described.

In testimony whereof I affix my signature in presence of two witnesses.

JOSEPH W. ROSS.
